Attorney Geo. W. Tibbitts

UNITED STATES PATENT OFFICE.

THEODORE ENDEAN, OF CLEVELAND, OHIO.

PHOTOGRAPHIC CHAIR.

SPECIFICATION forming part of Letters Patent No. 398,712, dated February 26, 1889.

Application filed January 9, 1888. Serial No. 260,252. (No model.) Patented in Canada August 31, 1887, No. 27,531; in France September 20, 1887, No. 185,967, and in England September 20, 1887, No. 12,733.

all whom it may concern:

Be it known that I, THEODORE ENDEAN, of Cleveland, in the county of Cuyahoga and State of Ohio, have invented certain new and useful 5 Improvements in Photographers' Chairs, of which the following is a specification.

In the accompanying drawings, Figure 1 is a perspective view of my photographer's chair. Fig. 2 is a vertical section of the same. Fig. 10 3 is a perspective view of the chair as arranged with the baby-holding attachment. Fig. 4 is a detached and enlarged view of back-rest-adjusting mechanism. Fig. 5 is a detached and enlarged view of head-rest adjusting and holding mechanism in connection with the platform. Fig. 6 is a detached and enlarged view of an adjustable clamp for holding the head-rest rod to vertical rod. Figs. 7, 8, 9, and 10 are detached views of the separate parts composing said clamp.

A is a platform, which I make, preferably, in circular form, though other shapes may be made, if desired, and it is mounted on casters *a a*, for the convenience of readily moving it about.

B is a hollow pedestal secured to the center of said platform.

C is a revolving seat, supported in said pedestal by means of a central spindle, D, having 30 a shoulder and reduced portion, *d*, incased in a spring, *d*², standing on the floor of the platform, with its upper end bearing against the shoulder and supporting the spindle. Said spring, when free, supports the seat a short 35 distance above the top end of the pedestal, as seen in Fig. 2. The lower end of the spindle projects below the platform and engages with one end of a lever, E, fulcrumed at its middle part to a short hanger, *e*, secured to the under 40 side of the platform. The other end of said lever E carries a brake-pad, F, which bears upon the floor upon which the platform stands. It is also provided with a spring surrounding its spindle, and passing between it and the 45 under side of the platform. The purpose of the brake is to hold the chair from moving while a person is stepping onto or off from the platform. Then when the person is seated his weight depresses the lever E and lifts the 50 brake-pad from the floor. Then the operator

may easily move the chair and sitter for perfect adjustment of position.

At one side of the seat C is attached an adjustable back-rest consisting of a bracket, G, having a circular head provided with teeth on 55 its periphery.

H is an arm-socket, having a horn, *h*, forming a pawl with teeth, which engage with the teeth on the head of the bracket. The socket H is jointed to the head of the bracket by 60 links *H*², pivoted to both and forming a double joint. A spring is interposed between the head G and the pawl, and serves to keep the pawl in contact with the head.

I is an arm secured in the socket H, and is 65 provided with an adjustable pad, J.

At one side of the seat is attached an adjustable arm-rest, consisting of a slotted bracket, L, having a socket, *l*, for the stem M of a support, N, and is provided with a set-screw, O, for enabling the said support to have vertical and lateral adjustment. To the platform is also attached an adjustable head-rest, consisting of a lever or bar, P, pivoted at the inner end by an eye formed thereon, and 70 through which the lower end of the spindle D passes. Attached to its outer and moving end is a hollow post, Q, in which is placed a vertically-adjustable rod, R, having the adjustable head-rest arm S attached to its top, 75 and capable of being held at any required height by means of a set-screw, S². The bar P has a transverse cross-arm, *p*, provided with rollers *u u*, journaled in recesses in each end thereof, and which roll on the under curved 80 edge of the platform as the said bar is moved from side to side.

V V are arms projecting downward and inward from the post Q, also provided with rollers which roll upon the upper curved edge of 85 the platform on a metal track.

A fastening device for holding the head-rest at any required place at the side of the platform is provided, consisting of a short lever, T, pivoted in a slot in the lower end of the 90 post Q. The outer end of said lever T is connected by a rod, T², to a hand-lever, T³, resting on an arm, *p*², on the post Q. The rod T² is pivoted at one corner of the head of the 95 said lever T³, so that the turning of said lever 100

upright draws upon the rod T^2 , and thereby pulls on the lever T and causes its inner end to press upon the metal track on the edge of the platform and bind the post fast.

5. A swivel-clamp for adjustably holding the head-rest rod S to the vertical rod R consists of two plates, W W^2 , the upper ends of which are in disk form, while the lower ends have recesses in their inside faces, which fit over 10 the head on the end of rod R .

W^3 is a disk having a hole, X , through which the said rod S passes, and also has in one face an opening connecting with the said hole X , and into which a projection, X^2 , on the face of 15 plate W fits and bears against the side of the rod S . On the side of the disk W^3 opposite to the said opening is a projection, X^3 , which fits into a recess, X^4 , in the face of plate W^2 , and forms a journal for the said disk W^3 to turn on. On the face of the plate W is also made a projection, X^5 , having a screw-threaded opening, into which a screw, X^6 , passed through a hole, X^7 , in plate W^2 , is screwed for holding all firmly together. The screw X^6 has a lever, 20 X^8 , attached, by which it is turned. This device admits of universal adjustment of the head-rest.

In Fig. 3 is seen an attachment for holding babies to the arm-rest, consisting of a rod, 30 R^2 , secured to the rod M of the arm-rest N by means of a bracket-arm, M^2 , having sockets and set-screws m m for adjustably securing them together. b b are side supports attached to the rod R^2 by set-screws, which, in 35 connection with the arm-rest N , forms a suitable seat for a baby. c c are arms, also attached to rod R^2 by set-screws, which are intended to clasp the body of the baby and hold it to the seat. d d is a head-rest attached to the top of a cap-piece, d^2 , which sets upon the top of rod R^2 . It has a slot, d^3 , in which is a strap, also intended for assisting in securing the baby to the seat.

Y is a detachable arm for supporting a reflecting-canopy over the sitter. Said arm is hooked into a socket, z , on the pedestal B , and carries an upright tubular rod, Z , into which is fitted a sliding extension-rod, Z^2 , held at any suitable height by set-screw z' . To the 45 top end of rod Z^2 is attached a rod, Z^3 , by means of an adjustable clamp, like that

shown in Fig. 6. To one end of rod Z^3 is attached a light frame, z^2 , having several panels provided with sliding curtains z^3 z^4 z^5 z^6 , &c., which may be drawn to obscure the light 55 more or less, as may be desired.

Having described my invention, I claim—

1. In a photographer's chair, the combination, with a platform supported on casters, of a hollow pedestal supporting a revolving seat, 60 having a central spindle setting in said pedestal upon a spring, said spindle also connected with and operating a brake-lever and pad, substantially as described.

2. In a photographer's chair, the combination, with the seat C , of an adjustable back-rest consisting of a bracket, G , having a ratchet-toothed head, an arm-socket, H , having a pawl, h , and joined to the head G by links H^2 , arm I , and adjustable pad J , all constructed to operate substantially as described. 65

3. In a photographer's chair, the combination, with the platform A , of the bar P , having cross-arms p p , provided with rollers n n , the hollow post Q , having arms V , provided with rollers, and the lever T , connected by rod T^2 to hand-lever T^3 , all constructed to operate 70 substantially as described. 75

4. The combination, with rods R and S of the head-rest, of the adjustable swivel-clamp 80 consisting of the two plates W W^2 , each having a recess for embracing the head of rod R , and having the recesses X^2 and X^4 , the disk W^3 , having a recess in one side and in communication with hole X , through which rod S 85 passes, and a journal projection, X^3 , and a hand-lever screw, X^6 X^8 , for screwing with threaded hole X^5 of plate W , for binding and clamping the disk W^3 and rod S and the head of rod R together, substantially as shown and 90 described, and for the purpose specified. 85

5. The rod Y , tubular rod Z , extension-rod Z^2 , held by set-screw z' , and rod Z^3 , attached to and held by swivel-clamp Z^4 , and having adjustable curtain-canopy, in combination with 95 chair-pedestal B , all constructed to operate substantially as described.

THEO. ENDEAN.
